a corporation of Delaware

Application April 30, 1952, Serial No. 19,522

Term of patent 14 years

(Cl. D48—4)

To all whom it may concern:

Be it known that I, Viktor Schreckengost, a citizen of the United States of America and a resident of Cleveland, in the county of Cuyahoga and State of Ohio, have invented a new, original, and ornamental Design for a Lighting Fixture, of which the following is a specification, reference being had to the accompanying drawing, forming a part thereof.

In the drawing:

Figure 1 is a perspective view of a lighting fix-

ture taken from above and showing my new design;

Figure 2 is a side elevation view thereof; and Figure 3 is a front elevational view thereof. The portion B of the design below the bracket A is a light transmitting bowl or globe.

I claim:

The ornamental design for a lighting fixture, as shown and described.

VIKTOR SCHRECKENGOST.
